ATTORNEY

UNITED STATES PATENT OFFICE.

ALFRED P. BABCOCK, OF NEW YORK, N. Y.

DESIGN FOR A GLASS BOTTLE.

SPECIFICATION forming part of Design No. 31,780, dated November 7, 1899.

Application filed September 21, 1899. Serial No. 731,228. Term of patent 3½ years.

To all whom it may concern:

Be it known that I, ALFRED P. BABCOCK, a citizen of the United States, residing at New York city, in the borough of Manhattan, State of New York, have invented and produced a new and original Design for Glass Bottles, of which the following is a specification, reference being had to the accompanying drawings, forming part thereof.

- o Figure 1 is an elevation of the bottle, showing my design. Fig. 2 is a cross-section taken on line $x\ x$ of Fig. 1.

As shown in the drawings, the leading feature of my design consists of a glass bottle whose cylindrical-shaped neck C curves outwardly at its base and terminates in a vertically-arranged annular plane D, the latter of

which arises from the plane surface E, the outer edge of said plane E terminating in an obtuse angle F, from the lower portion of which extends downwardly and outwardly the bell curve G, ending as it does in the vertically-arranged plane surface H, from the lower edge of which extends the ogee curve I.

Having described my invention, what I claim as new, and desire to secure by Letters Patent, is—

The design for a glass bottle, substantially as shown and described.

ALFRED P. BABCOCK.
